UNITED STATES PATENT OFFICE.

ROY R. IRELAND, OF EAST ORANGE, AND ALBERT F. F. GILSON, OF CLOSTER, NEW JERSEY, ASSIGNORS TO WESTERN ELECTRIC COMPANY, OF NEW YORK, N. Y., A CORPORATION OF ILLINOIS.

TELEPHONE HAND SET.

1,075,423.

Specification of Letters Patent. Patented Oct. 14, 1913.

Application filed April 1, 1913. Serial No. 758,214.

To all whom it may concern:

Be it known that we, ROY R. IRELAND and ALBERT F. F. GILSON, citizens of the United States, residing at East Orange, in the county of Essex and State of New Jersey, and at Closter, in the county of Bergen and State of New Jersey, respectively, have invented a certain new and useful Improvement in Telephone Hand Sets, of which the following is a full, clear, concise, and exact description.

This invention relates to telephone hand sets and has for its object to provide a device of this class of few, simple and inexpensive parts, which parts may be easily manufactured and readily assembled.

In accordance with this invention the parts of the hand set are made up for the most part of stamped and molded parts of simple design, one of the features being the provision of a main support for the part which is so formed as to support the transmitter and receiver at the proper angle when in use and to constitute three sides of an inclosure in which the circuit-connecting parts are mounted.

Another feature of this invention relates to the contact supporting blocks which are formed free of molded-in parts, and are so constructed that the terminals may be readily secured thereto.

Other features of this invention are the details of construction and assembly of parts, as will hereinafter more fully appear.

In the drawings illustrating this invention—Figure 1 is a view in side elevation with a part in section of a set embodying this invention; Fig. 2 is a view in front elevation with parts broken away and parts removed of a device embodying this invention; Fig. 3 is a view in perspective of parts constituting the handle of a set made in accordance with this invention; and Fig. 4 is a detail perspective view of a mounting block constituting one feature of this invention.

As shown in the drawings, there is provided a mounting plate comprising a back portion 5 constituting a support for mounting blocks and having end portions 6 and 7 with angular extensions 8 and 9 thereon for supporting a transmitter 10 and a receiver 11. A cover comprising a top member 15

and side members 16 and 17 is adapted to be secured to the mounting plate by means of screws extending through said top member and engaging screw-threaded studs 18, 18 secured to the back portion 5 and to form with said portions 5 and the end portions 6 and 7 a complete inclosure.

Secured to the inner face of the back portion 5 are two insulating blocks 20 and 21 each carrying two pairs of stationary contact lugs 22, 22 and 23, 23. As shown each of the blocks 20 and 21 is rectangular in shape and is provided with two openings 24 and 25. Located in opposite sides of the openings 24 and 25 are metal nuts 26 and 27 for screws 28, 28 passing through the sides of said mounting blocks 20 and 21 to secure the contact lugs 22, 22 and 23, 23 thereto. Screw-threaded apertures 30, 30 in the sides of the insulating blocks 20 and 21 receive terminal screws 31, 31 which retain said stationary contact lugs 22, 22 and 23, 23 against rotation and receive terminal clips secured to conductors 35, 35 forming the circuit connections of the device.

Mounted upon each of the blocks 20 and 21 is a contact-closing spring 36 normally in engagement with the upper stationary contact lugs 22, 22 but arranged to be moved into engagement with the lower contact springs 23, 23 by means of push buttons controlled from the outside of the handle portion of the hand set.

The contact-closing spring 36 at the upper end of the hand set is normally used for signaling and is operated by a cylindrical button 37, the inner end of which rests upon said spring, the outer end thereof being reduced in diameter and extending outwardly through an opening 38 in the top member 15 of the cover in position to be actuated by the user of the set. The contact-closing spring 36 at the lower end of the set controls the talking circuit of the instrument and is operated by means of a rectangular push member 40 mounted upon the free end of a spring 41, the opposite end of which is secured to the inner face of the top member 15 of the cover. The rectangular push member is located in position to be engaged by the digits of the user when the device is held in position for talking. Each contact spring 36 is secured to its insulating block 105 by means of a screw 42 which passes through

said spring and block and engages a nut 43 located in a cut-away portion 44 in the lower face of the block, as shown in Fig. 4.

The top member 15 of the cover is provided 5 with notches 45 and 46 at its ends through which conductors may be led to the transmitter and receiver. An opening 47 is provided through the right-angled end portion 6 through which a telephone cord 48 may be 10 led.

The main supporting member and the cover are each formed of a single piece of sheet metal stamped into shape and the contact springs 22, 22 and 23, 23, as well as the 15 contact-closing parts, are all stamped parts, while the supporting blocks are merely molded into shape without molded-in parts. The set is thus composed of parts which may be formed in the simplest and most economical 20 manner possible and may be easily assembled into a compact and durable structure. Furthermore, by reason of the fact that there are no molded-in parts in the mounting blocks, any of the parts thereof may be 25 easily replaced without replacing the entire block.

We claim:

1. In a telephone hand-set, the combination with a transmitter and a receiver, of a 30 supporting member therefor having a back portion and two end portions, a cover therefor forming with said supporting member a complete inclosure, and spring mounting blocks carried by said supporting member.
2. In a telephone hand-set, the combination with a transmitter and a receiver, of a 35 supporting member therefor comprising a metal stamping having a back portion and two end portions, spring mounting blocks 40 carried by said back portion, and a cover comprising a stamped member forming with said back portion and said end portions a complete inclosure for said spring mounting blocks.
3. In a telephone hand-set, the combina- 5

tion with a transmitter and a receiver, of a support therefor comprising a metal stamping having a back portion and two end portions, spring mounting blocks carried by said back portion, and a metal stamping comprising a top portion and two side portions completing with said support an inclosure for said mounting blocks. 50

4. In a telephone hand-set, the combination with a transmitter and a receiver, of a 55 supporting member therefor bent intermediate its ends to form three sides of an inclosure, a cover for completing said inclosure, switch springs, a mounting block therefor located within said inclosure, and 60 externally controlled means for operating said switch openings.

5. In a telephone hand-set, the combination with a transmitter and a receiver, of a 65 support therefor bent intermediate its ends to form the bottom and two ends of an inclosure, a removable cover therefor forming the top and two sides of said inclosure, switch springs, a supporting block therefor mounted upon said transmitter and receiver 70 support, and a plunger member for operating said springs flexibly supported upon the interior of said cover and extending therethrough.

6. In a telephone hand-set, the combination with a transmitter and a receiver, of a 75 support therefor, insulating blocks removably mounted upon said support, switch springs removably mounted upon said insulating blocks, a removable cover for said 80 spring-carrying blocks, and spring-actuating means carried by said cover.

In witness whereof, we hereunto subscribe our names this 27th day of March A. D., 1913.

ROY R. IRELAND.

ALBERT F. F. GILSON.
